Joseph D. Portanova, Arcadia, Calif., assignor to Hoffman Radio Corporation, a corporation of California

Application July 14, 1953, Serial No. 25,942

Term of patent 7 years

(Cl. D56—4)

To all whom it may concern:

Be it known, that I, Joseph D. Portanova, a citizen of the United States of America, residing at Arcadia, in the county of Los Angeles, State of California, have invented a new, original, and ornamental Design for a Television Cabinet or Similar Article, of which the following is a specification, reference being had to the accompanying drawing, forming a part hereof.

The rear of the cabinet is plain and unornamented.

I claim:

The ornamental design for a television cabinet or similar article, substantially as shown and described.
